INVENTOR.

William E. Nickerson

UNITED STATES PATENT OFFICE.

WILLIAM E. NICKERSON, OF CAMBRIDGE, MASSACHUSETTS.

SPEED-REGULATOR FOR ELEVATORS.

SPECIFICATION forming part of Letters Patent No. 398,972, dated March 5, 1889.

Application filed November 30, 1888. Serial No. 292,234. (No model.)

To all whom it may concern:

Be it known that I, WILLIAM E. NICKERSON, of Cambridge, in the county of Middlesex and State of Massachusetts, have invented 5 a new and useful Improvement in Fluid Speed-Regulators for Elevators, of which the following, taken in connection with the accompanying drawings, is a specification.

The object of my invention is to combine 10 with a fluid speed regulating-cylinder and its operating parts an independent device that shall regulate the amount of restriction to which the restraining-fluid in its flow from one side of the piston to the other is to be 15 subjected. This object I attain by the mechanism shown in the accompanying drawings, in which—

Figure 1 is a front elevation of one form of 20 my device as applied to a fluid speed-regulator. Fig. 2 is a side elevation of the same, (cylinder not shown;) and Fig. 3 is an enlarged section in detail.

In Figs. 1 and 2 of the drawings, A represents a drum, A' a safety-rope, and C a counterbalance-rope. At each end of the shaft 25 A² of the drum A, I have a crank-disk, B, and a crank-pin, B'.

In the drawings I have shown two fluid speed-regulating devices, one at each end of 30 the drum-shaft, although one such device might do the work required.

Each of the fluid speed-regulating devices that I have chosen for the purpose of illustrating my invention consists of a cylinder, 35 C, in which a piston (not shown) works.

P is the piston-rod, which is connected to the cross-head L', said cross-head L' being guided by ways L² L³, and is connected to the crank-pin B' by the link L, so that the drum 40 A cannot revolve except the piston in the cylinder C traverses, and as the motion of the piston is governed by the passage of fluid from one side of it to the other (in this case

wholly or partly through the pipe H³) it is evident that the speed of the drum A is controlled by the said passage of fluid. 45

My invention consists in adding to a fluid speed-regulating device an independent governor, the function of which shall be to regulate the amount of restriction given to the 50 flow of fluid from one side of the piston to the other.

I will now describe the form of governor and its adjuncts that I have selected for application in this case. 55

D³, Figs. 1 and 2, shows an ordinary ball-governor, the sliding stem D⁴ of which operates the lever E², E having a fulcrum at E', and through it the links H H, which in turn raise or lower the levers H' H'. Each of the 60 levers H' H' gives a rotary movement to the plug-valve H², working in its socket-piece H⁴, connected to the pipe H³, (see Fig. 3,) and as some of the fluid in the cylinder C has to flow through the pipe H³ at each movement of the 65 piston it is evident that the rapidity of flow of fluid through the pipe H³ must have a definite relation to the speed of the drum A, and as this velocity of flow depends upon the opening in the plug-valve H² H⁴ it must of necessity depend also on the position of the lever H', which is controlled by the governor D³. The governor D³ is driven by the beveled gear D on the drum-shaft A² through the gear D' and shaft D², Figs. 1 and 2. 70

I claim—

In a fluid speed-regulating device, the combination of a governor, D³, intermediate connections, and valve H² H⁴, with the pipe H³, and fluid-cylinder C, substantially as described, and for the purpose set forth. 80

WILLIAM E. NICKERSON.
